CHARGE FORMING MANIFOLD

Albert H. Hoops, Savannah, Ga.

Application August 31, 1937, Serial No. 161,843

8 Claims. (CL 123—127)

The invention relates to charge forming manifolds and has as an object to provide an improvement in a device of this nature to enable the operation of an internal combustion engine utilizing oil heavier than gasoline as a fuel.

It is a further object of the invention to provide a device of the character indicated utilizing gasoline as the starting fuel and having means to apply ample heat to a heavier oil used as a fuel after the motor is warmed up.

It is a further object to provide a device which will "warm up" in a minimum time.

It is a further object to provide an oil heating manifold in which the exhaust gases will have very short and direct paths to the points of application of heat to the intake passages.

It is a further object to provide a manifold causing low back pressure of exhaust gases on the motor, and reducing noise of explosion.

It is a further object to provide means enabling an accurate control of the temperature applied to the fuel whereby correct temperature may be secured for gasoline alone, heavier oil alone, or any percentage of either combined with the other.

Further objects of the invention will appear from the following description when read in connection with the accompanying drawings showing an illustrative embodiment of the invention and wherein:

Fig. 1 is a side elevation of an engine equipped with a manifold of the invention, the cover plate of the latter being omitted;

Fig. 2 is a plan view of the structure of Fig. 1;

Fig. 3 is a detail horizontal section on line 3—3,

Fig. 1;

Fig. 4 is a horizontal section of the manifold only on line 4—4, Fig. 1;

Fig. 5 is an end view of the manifold seen from the right of Fig. 1;

Fig. 6 is a vertical section on line 6—6, Fig. 4;

Fig. 7 is a plan view of the intake manifold portion of the device partly broken away;

Fig. 8 is a side elevation of the structure of Fig. 7 partly broken away;

Fig. 9 is a plan view, and Fig. 10 is a side elevation of a baffle assembly.

Fig. 11 is a side elevation of another form of baffle;

Fig. 12 is an end view of the structure shown in Figs. 9 and 10;

Fig. 13 is a side elevation of the exhaust valve; and

Fig. 14 is a diagrammatic view of the fuel pump circuits.

As shown the main portion of the device com-

prises two parts, namely, a casting 15 which may be of cast iron, duraluminum, or the like, and an intake manifold assembly 16 shown by itself in Figures 7 and 8 desirably formed of a metal of high heat conductivity as copper.

The casting 15 is shown as formed with ports 17, 18 adapted to register with the exhaust ports of an internal combustion engine.

The device as illustrated is adapted for application to a six-cylinder engine and as shown the ports 17 at each end of the casting will accommodate one cylinder each of the engine and the intermediate ports 18 two cylinders each. The casting 15 is formed with openings at 19, 20, 21 to fit the projecting conduits 22, 23, 24 of the intake manifold assembly, the said conduits being placed in the openings 19—21 and welded therein. The interior of the casting 15 is shown as divided into two portions by means of walls 25, 26, and 27.

Between the edges 26 and 27 there is placed a valve seat 28 and an elongated flap valve 29 is mounted in bearings 30, 31 to swing into the open position shown in Figure 6 or into position closing the elongated opening in the valve seat 28.

As shown, the valve 29, desirably of cast iron, is cast with a stiffening rib 29' to prevent parping of the valve under influence of the heat of the exhaust gases.

The exhaust ports 17 and 18 are each formed with a wall 32 curving downwardly to meet the wall 27 whereby when the valve 29 is in the open position of Figure 6 the exhaust gases will all find access to the enlarged chamber 33 in which the intake manifold 16 is located, said exhaust gases passing in said chamber 33 to an exhaust port 34 to be connected to an exhaust pipe leading to the usual muffler.

When the valve 29 is closed, the exhaust gases pass downwardly to the elongated chamber 35 and cut through the port 36, Figures 4 and 6, which is also connected to the same exhaust pipe. To control the valve 29 there is shown a rod 37 leading from the dash to bell crank 38 pivoted at 39 upon a portion of the casting 15, the remaining end of the bell crank being connected by link 40 to an arm 41 rigidly connected to a sliding rod 42 connected at its lower end to arm 43 rigid with the valve 29.

The intake manifold 16 is shown as formed of an elongated conduit portion 44 having the connection at one end by means of elbows 45, 46 with conduit 22 having an opening in its side connected with a conduit 47 connected by elbows 48, horizontal portion 49, elbow 50, upwardly ex-

tending portion 51, elbow 52, horizontal portion 53, elbows 54 and 55 with conduit 23.

The remaining end seen at the right of Figures 7 and 8 of conduit 44 is shown as connected by elbows 56, 57 with extension 24. The purpose of the form of conduits shown is to provide paths of equal length for fuel to each port whereby to supply fuel of the same temperature to each cylinder.

10 The entire fuel for the different intake ports is delivered to the conduit 44 through a port 58 connected by the vertical conduit with the valve chamber 59 to which fuel is supplied by the carburetors 60, 61.

15 Seating upon the upper portion of the casting 15 is the valve housing 62 formed of two castings 63, 64, the former being cast with a socket 65 into which a projecting flange 66 on casting 64 telescopes. The two castings 63 and 20 64 are secured together by means of cap screws 67.

25 The carburetor 60 is coupled to the casting 63 and the carburetor 61 to the casting 64 so that both carburetors are connected to deliver to the valve chamber 59 in which slides the valve 68 to seat alternately with seat 69 or seat 70. The valve 68 is controlled by link 71 leading to the dash of the vehicle.

30 One of the carburetors 60 is to be connected to the source of supply of gasoline and the other thereof to a source of supply of heavier oil and the valve 68 will be seated upon the appropriate seat to deliver only gasoline when the motor is cool. As the motor warms up the valve may be shifted to draw a mixture of gasoline and heavier oil or when fully warm, the valve may be placed against the seat to close off the supply of gasoline to deliver only oil to be used as fuel to the motor. At any time when service requires, the 35 combination of two fuels may be fed to the motor.

40 The two carburetors 60, 61 may obviously be controlled by a single connection to the accelerator pedal of the vehicle and the two butterfly valves will both be opened simultaneously or conversely closed simultaneously without effect upon 45 the nature of the fuel supply otherwise than as it is controlled by the valve 68.

45 The manifold 16 is shown as provided in its conduit portion 44 with a rod 71 carrying baffle plates 72, 73, the arcuate portions 74, 75 of the baffle plates contacting with the inner wall of the conduit.

50 In the remaining course of the passage of fuel through the portions of the intake manifold, baffles of the nature shown in Figure 11 at 76 are provided whereby to provide a tortuous passage for the fuel to submit the same to a maximum heating effect. It will be seen that the path of 55 exhaust gases into the heating chamber 30 is direct from the exhaust ports of the motor through the elongated valve opening controlled by valve 29, and when these exhaust gases are directly delivered to the large chamber 33, or 35, a minimum of back pressure upon the motor will be produced. This reduction in pressure will cause the 60 muffler of the motor to be more effective and will reduce the explosive noise of the running of the motor.

65 The intake connections between the portions 22, 23, 24 of the intake manifold and the conduit portion 44 thereof are designed to provide a substantially uniform heating effect upon the fuel delivery to each of the cylinders of the motor which is an important feature of the invention 70 for smooth operation of the motor.

The casting 15 is shown as formed with a cover plate receiving flange 77 to which cover plate 78 is applied in use. Asbestos lagging of substantial thickness is provided upon the exterior of casting 15 and cover plate 78.

5 To remove the valve 29 from the chamber 33 without removing the intake assembly, an opening 86 is provided in casting 15 and provided with a closure plate 87.

10 To supply fuel to the carburetors electrically driven pumps 79, 80, one for each carburetor, are provided. A switch 81 is shown having contacts 82, 83 one for control of each pump and a movable contact 84 controlled in common with the operating link 85 for valve 68. The width of 15 contact 84 is such that both pumps 79, 80 will be in operation at all times when a combination of fuels is being drawn.

15 To cause the valve 68 to be firmly pressed to either seat when using one fuel alone, a past center spring device 85 is utilized.

20 It is obvious that to guide the operator any heat indicator as a pyrometer may be placed in the intake manifold as in "24", with an indicator on the dash of the vehicle. The location of the portion 44 of the intake assembly directly in front of the elongated port of valve 29, and the location of the portions 45 and 49 in the path of flow of the exhaust gases make ample quantities of 25 heat available to be applied to the fuel mixture. The diameters and lengths of the intake passages 30 may be so chosen, in the presence of the heat available, to secure any maximum desirable heat of the fuel mixture. The operator can therefore by adjustment of the valve 29 provide optimum 35 heat conditions for the fuel used.

30 The invention may be adapted to engines of other than six cylinders by appropriate changes in the number of ports and of intake assembly 40 passages in an obvious manner.

35 Minor changes may be made in the physical embodiment of the invention within the scope of the appended claims without departing from the spirit thereof.

40 I claim:

45 1. A charge forming manifold comprising, in combination: a shell having openings to register with the respective inlet and exhaust ports of an internal combustion engine; internal walls in said shell dividing the interior thereof into a heat chamber and a bypass chamber; an intake-manifold assembly housed in said heat chamber formed with intake passages secured in the intake-port-registering openings of the shell; means to introduce an explosive mixture of air 50 and fuel to said intake-manifold assembly; one of said internal walls formed with a port to pass exhaust gases to said heat chamber; valve means to at will cause the exhaust gases to enter the desired one of said chambers; said shell formed with an outlet port from each of said chambers and means to at will feed an explosive mixture of air and a chosen one of a plurality of fuels to said 55 intake manifold assembly.

60 2. A charge forming manifold comprising, in combination: a shell having openings to register with the respective intake and exhaust ports of an internal combustion engine; internal walls dividing the interior of said shell into heat and bypass chambers; one of said walls formed with an elongated port extending past said exhaust openings to provide direct flow from a plurality of said openings into said heat chamber; a valve to control said port and by closure thereof to direct exhaust gases to said bypass chamber; an in- 65

take assembly formed of material of high heat conductivity housed in said heat chamber in front of said elongated port, and having passages secured in said intake-port-registering openings; 5 and means to at will feed an explosive mixture of air and gasoline or oil to said intake assembly.

3. A charge forming manifold comprising, in combination: a shell formed with openings to register with the intake and exhaust ports of an 10 internal combustion engine, internal walls dividing said shell into a heat chamber and a bypass chamber; an intake assembly housed in said heat chamber comprising a conduit to be placed into communication with carburetion apparatus; conduits 15 to be placed into communication respectively with the said intake openings and conduit means connecting each of the said last named conduits with the carburetor conduit formed to provide paths for fuel of equal length from the 20 carburetor conduit to the respective intake conduits; one of said internal walls provided with a port; a passage from each of said exhaust-port-registering openings leading to said port to conduct exhaust gases to said heat chamber; a valve 25 controlling said last named port to direct the exhaust gases into said bypass chamber and means to at will feed an explosive mixture of air and either gasoline or heavier oil to said intake assembly.

30 4. A charge forming manifold comprising, in combination: a shell having openings to register with the intake and exhaust ports respectively of an internal combustion engine; an interior vertical longitudinal wall spaced from said openings; 35 other internal walls extending from the lower edge of said vertical wall to completely divide said shell into a heat chamber and a bypass chamber; lateral extensions of said vertical wall surrounding the exhaust port registering openings of said shell; said vertical wall having an elongated port extending continuously past a plurality of said exhaust passages to provide a substantially direct path for gases from each of said exhaust ports to said heat chamber; an elongated 40 flap valve pivoted adjacent its lower edge to control said port whereby said valve when opened closes the opening into said bypass chamber and directs gases to said heating chamber; an intake assembly housed in said heat chamber and having 45 conduit extensions secured in each of said intake port-registering openings; means to introduce at will an explosive mixture of either light or heavy fuel and air into said intake assembly; and means to control said flap valve.

55 5. A charge forming manifold comprising, in combination: a shell having openings to register with the intake and exhaust ports of an internal combustion engine; an opening to communicate with carburetor apparatus; means dividing the 60 interior of the shell into heat and bypass chambers, each of said chambers having an outlet opening to be placed into communication with an exhaust pipe; an intake assembly of copper piping housed in said heat chamber and having extensions secured in each of said intake-registering 65 openings and an extension to be placed in communication with carburetor apparatus; a valve chamber seating upon said shell having a valve chamber therein provided with opposite ports; a 70 sliding valve in said chamber to seat upon said ports alternatively; a carburetor to supply fuel

mixtures of different character to each of said opposite facing ports; an electric pump to supply fuel to each of said carburetors; switch means to control the motors driving said respective pumps; common means to control said switch means and said valve whereby when either kind of fuel is being supplied by its pump with the valve in full open position for said fuel the remaining pump is quiet.

6. A charge forming manifold comprising, in combination: means to heat a fuel mixture by exhaust gases; means to accurately control the amount of heat applied to said mixture; a plurality of carburetors each connected to supply a different grade of fuel to said heating means; 15 valve means adjustable to supply at will one only of said different fuels or any desired percentage mixture of different fuels; electric pumps to supply fuel to said carburetors; switch means to control said pumps operable in common with the control of said valve means; said switch means having a slidable contact to bridge contacts for each of said pumps in all intermediate positions of said valve for delivering mixtures of fuel and in extreme positions of said valve to put 25 out of operation the appropriate pump.

7. A charge forming manifold comprising, in combination: means to heat a fuel mixture by exhaust gases; means to accurately control the amount of heat applied to said mixture; a plurality of carburetors each connected to supply a different grade of fuel to said heating means; 30 valve means adjustable to supply at will one only of said different fuels or any desired percentage mixture of different fuels; pumps to supply fuels 35 to said carburetors; means to control said pumps operable in common with the control of said valve means; said pump control means including means to cause operation of each of said pumps in all intermediate positions of said valve means for 40 delivering mixtures of fuel, and in extreme positions of said valve to put out of operation the appropriate pump.

8. A charge forming manifold comprising, in combination: an elongated shell having an open 45 side and a cover plate for closing said side; heat insulating layers covering said shell and said cover plate respectively; internal wall structure dividing said shell longitudinally into heat and bypass chambers; said shell formed with openings to register with the intake and exhaust ports respectively of an internal combustion engine; intake conduits in said heating chamber formed with passages in communication with said intake registering openings and a passage for carburetor 50 connection, an elongated valve opening extending past a plurality of said exhaust-port-registering openings; a flap valve hinged at an edge of said elongated port to deflect gases into said heat chamber or said bypass chamber at will; said 55 shell formed with an opening at an end opposite said valve structure for removal of the valve without disassembly of the structure; said shell having openings from the respective chambers to be placed in communication with an exhaust pipe 60 a plurality of carburetors connected to said passage and fed with fuels of differing boiling points; and means to draw from a chosen one of said carburetors at will.
